FABRICIO DE ALBA B., OF PANAMA, PANAMA.

FLUSHING APPARATUS.

932,939.

Specification of Letters Patent. Patented Aug. 31, 1909.

Application filed November 12, 1908. Serial No. 462,354.

To all whom it may concern:

Be it known that I, FABRICIO DE ALBA B., a citizen of the Republic of Panama, residing at Panama city, in the Republic of Panama, have invented new and useful Improvements in Flushing Apparatus, of which the following is a specification.

This invention relates to flushing apparatus for water closets and the like, the object of the invention being to provide an apparatus of this character which dispenses with the ordinary valve controlled discharge outlets, and obviates the objections incident thereto, and which embodies a discharge pipe operating by a siphoning action to effect the discharge of the water from the tank for the purpose of flushing the bowl when the water in the tank reaches a determined height, together with a float controlled inlet valve operative to cut off the flow of water when the prescribed level is reached and adapted, through the action of the float, to coöperate with the discharge pipe to establish the siphoning action for the flow of the water from the tank to flush the bowl.

With these and other objects in view, the invention consists of the features of construction, combination and arrangement of parts hereinafter fully described and claimed, reference being had to the accompanying drawing, showing a vertical section of a flushing apparatus embodying the invention.

In the drawing, 1 designates a flush tank of any ordinary construction, to which the water is supplied through a feed pipe 2. The inner or discharge end of this pipe is provided with a valve seat 3 for a cut off valve 4. The valve 4 is movably mounted within a casing 5 having a threaded flange 6 to engage the threaded end of the pipe 2, and provided with an outlet 7 through which the water passes into the tank. The valve is mounted upon one end of a threaded stem 8 slidably mounted in openings 9 and 10 formed in the body of the valve and depending portion of a bracket arm 11 extending from the valve casing. Mounted on the outer end of the stem is a suitable finger piece 12, and mounted on the threaded portion of the stem between the casing and the said depending portion of the bracket is a threaded sleeve or nut 13 carrying a lug or projection 14.

A valve controlling lever 15 is pivotally

mounted at its inner end upon a pivot pin 16 carried by the valve casing and has such end bifurcated or forked to receive the lug and to provide front and rear projections 17 and 18 to engage the same. The outer end of the lever is formed with an eye 19 or otherwise suitably constructed for the attachment thereto of an operating rod or chain by which the lever may be tilted on its pivot to open the valve. When the outer end of the lever is drawn downward the projection 17 engages the lug 14 and slides the valve open for the feed of water to the tank, and when said end of the lever is elevated the lug 18 engages the lug 14 and slides the valve to a closed position to cut off the flow of water. A link 20 or other suitable flexible support depends from the lever into the tank and carries a float 21. This float is controlled by the level of the water in the tank to operate the lever to open the valve when the water in the tank falls below a prescribed level and to close the valve to cut off the flow of water when the tank is filled to such level.

The water discharges from the tank through a siphon discharge pipe 22, which pipe is provided with a comparatively long discharge leg 23 extending downward from the water level through the bottom of the tank and threaded at its lower end for connection with a pipe leading to the bowl and to receive suitable clamping nuts 24 by which it is secured in position, and is also provided with a short leg 25 connected at its upper end with the upper end of the leg 23 by an elbow or return portion 26 and terminating at its lower end above the bottom of the tank.

In practice, the leg 25 of the siphon pipe is filled with water up to the maximum level, which is on a line a slight distance below the level of the lower portion of the elbow 26. Assuming that the tank is filled to the determined level and the valve 4 closed, it will be understood that in order to flush the bowl and to open the valve for refilling the tank when the charge therein is exhausted, it is simply necessary to pull down upon the rod, chain or operating device connected with the eye 19. By this action the valve is opened to allow water to feed into the tank, while at the same time the float 21 is forcibly depressed. This forcible depression of the float causes it to displace

the water below it, whereby the body of water in the tank is raised above its normal level. The water in the siphon leg 25 will accordingly be elevated and a portion will 5 pass up into the elbow 26 and discharge through the leg 23, thus creating a partial vacuum in the leg 23 and elbow 26, whereby a further and continuous flow of water from the tank is induced, the water continuing 10 to pass out through the discharge pipe until the siphoning action is broken by the lowering of the level of the water below the inlet end of the leg 25. When this occurs the discharge of the water is arrested, while the 15 valve 4 will remain open to allow water to feed into the tank through the pipe 2 until the normal level is again restored, when, through the elevation of the float 21 to its normal position, the valve will again be 20 closed to cut off the flow of water and the parts will be reset for the subsequent operation.

By employing a siphon discharge pipe constructed and arranged as described, the use 25 of the ordinary valved discharge outlet is obviated and the leakage attendant from the use of improperly seating valves prevented, and by the employment of a valve mechanism of the type disclosed it will be 30 seen that the float not only operates to restore the valve to closed position after each flushing operation, but also serves as a displacing medium to elevate the water in the tank to a proper degree above the normal 35 level to discharge the water through the siphon pipe when the operating device connected with the lever is actuated. By turning the stem 8 by means of the finger piece 12, the nut or sleeve 13 may be adjusted to 40 regulate the action of the lever 11 and the opening and closing movements of the valve 4, whereby the normal level of the water in the tank may be varied.

Having thus fully described the invention, what is claimed as new, is:—

1. A flushing apparatus comprising a tank, a siphon discharge pipe having its highest portion arranged above the normal water level of the tank, a water feed pipe, a valve controlling the inlet of water therefrom, a 45 sliding stem connected with the valve, an adjustable contact on said stem, a lever having spaced contact members to engage said adjustable contact, said lever being movable in one direction to open the valve and 50 in the reverse direction to close the same, and a float connected with the lever for moving the same to valve closing position and adapted when said lever is moved to valve opening position to elevate the water 55 in the tank to start the siphoning discharge action.

2. A flushing apparatus comprising a tank, a siphon discharge pipe having its highest portion arranged above the normal 60 water level of the tank, a water inlet pipe, a valve controlling the same, a sliding stem connected with the valve, a member adjustably mounted on the stem and provided with a projection, a pivoted lever provided with 65 cooperating projections to move the valve in reverse directions, said lever adapted to be manually operated in one direction to open the valve, and a float connected with the lever for moving the lever to valve closing position, said float being adapted on the 70 movement of the lever to valve opening position to raise the level of the water in the tank to establish the siphoning action.

In testimony whereof I affix my signature 80 in presence of two witnesses.
